GAME DEVICE

James H. Cannon, Los Angeles, Calif.

Application October 14, 1935, Serial No. 44,889

4 Claims. (Cl. 273—125)

My invention relates to a unit game device providing a playing field on which the game may be played, this unit game device being adapted to be used in groups so that a number of players may play the game at the same time or in competition on individual or separate playing fields.

It is an object of the invention to provide in a group of games of the above general character means wherein the attainment of a winning score by one of the players stops the play on all of the other game devices of the associated system of games.

A further object of the invention is to provide means whereby the game devices may be simultaneously returned to or replaced in condition for further play.

It is an object of the invention to provide a game device or unit comprising a playing field or board, at one end of which the player is positioned, and at the other end of which there is a turntable having openings therein adapted to receive a ball or balls, and switch means associated with these openings and adapted to be actuated by the passage of a ball into or through the openings, together with means for causing the actuation of indicating means, such, for example, as the illumination of lamps, corresponding to the placing of balls in, or the consecutive placing of a single ball in, the openings or pockets of the turntable.

It is a further object of the invention to provide a game device of the above character in which a winning score may be produced by the placing of the ball in several different combinations of openings or pockets. In respect to this, it is an object of the invention to provide a game device wherein a winning score is in part formed by the placing of a ball in a pocket of the turntable as it moves past a designated point or zone which may be indicated on the playing board of the game device.

A further object of the invention is to provide a game device of the above character having an indicator board with indicators thereon for showing the score, and a simple form of relay system for operation of the indicators and for stopping and starting the play on the game device or series of game devices arranged for use at the same time.

It is a further object of the invention to provide a game device having a turntable with pockets or openings therein, switch means carried by the turntable in such positions that they will be actuated by balls which enter or pass through the pockets or openings, there being means for

driving the turntable and means for connecting the switches with relays which are connected in a novel manner to produce novel effects in the operation of the game device.

It is a further object of the invention to provide a game device having a turntable with a designed form on the same, an indicator board having the same design thereon, and means for showing on the indicator board that the design has been completed and a winning score thereby produced.

Further objects and advantages of the invention will be brought out in the following part of the specification.

Referring to the drawings, which are for illustrative purposes only,

Fig. 1 is a plan view of a game device embodying the features of the invention.

Fig. 2 is a side view corresponding to Fig. 1, the side view being partly sectioned on a plane indicated by the line 2—2 of Fig. 1.

Fig. 3 is a front view of the game device shown in the preceding figures.

Fig. 4 is an enlarged sectional view taken as indicated by the line 4—4 of Fig. 2.

Fig. 5 is a fragmentary view looking upwardly toward the bottom of a part of the turntable of Fig. 4, as indicated by the arrow 5 of Fig. 4.

Fig. 6 is a bottom plan view taken as indicated by the arrow 6 of Fig. 4.

Fig. 7 is an enlarged, partly sectioned view of the back of the indicator board, showing a part of the relays and other associated structure, all of which are fully disclosed in the electrical diagram.

Fig. 8 is a sectional view taken as indicated by the line 8—8 of Fig. 7.

Fig. 9 is an electrical diagram of the operative parts of the game device.

As shown in Fig. 1, I provide a game device 20 which is used in duplicate, as will be hereinafter disclosed, such game device 20 having a table 21 equipped with a sloping playing board 22 having an aperture 23 at its front or leftward end 24 through which a ball, or balls, 25 may be lifted by a player who plays the game by rolling the ball or balls forwardly on the playing board 22. Near the back or rightward end of the board 22 is a circular opening 26 in which a turntable 27 is mounted so as to rotate. As shown in Figs. 2 and 4, this turntable 27 is carried by a spider 28 which is mounted on the upper end of a shaft 29 characterized by being tubular or hollow so that wires may be carried from the under surface of the turntable 27 to contacts disposed on the lower

part of the shaft 29 below the floor 31 with which the table 21 is provided. The turntable 27 is rotated by a driving means 32 consisting of a motor 33 and a reduction gear device 34 having a projecting shaft 35 on which there is a drive gear 36 engaging a driven gear 37 mounted on the lower end of the shaft 29, as shown in Fig. 6.

The turntable 27 has a pattern formed by a circle of openings 38 around the outer portion thereof, openings 41, 42, 43, 44, and 45 set in or defining the points of a star 39, and a central opening 40. Corresponding to the pattern or design of the turntable 27, the device has an indicator board 46 which is set in vertical position at the rearward end of the table 21 and has a replica of the pattern formed by an outer circle of indicators 48, indicators 51, 52, 53, 54, and 55 in the points of a star 49, and a central indicator 50.

As will be hereinafter explained, means are provided whereby the proper placing of a ball in one of the openings or pockets 38 will actuate the indicators 48, whereby the successive placing of the ball in the openings or pockets 41 to 45 inclusive will respectively cause the actuation of the indicators 51 to 55, and whereby the placing of the ball in the central opening 40 will cooperate in completing the playing of a game wherein a ball has been previously properly placed in one of the outer openings 38. In the form of game device shown, the indicators 48 include lamps 48a, the indicators 51 to 55 inclusive comprise lamps 51a to 55a, and the indicator 50 includes a lamp 50a. The lamps are disposed in separate chambers 57 in back of the front plate 58 of the indicator board 46 so as to be visible through windows 59. The lamps are held in sockets 61, and electrical connections are made therewith as indicated at 62 in Figs. 7 and 8, such electrical connections being given in detail in the wiring diagram, Fig. 9.

The game device is intended to be used with a number of other identical game devices set in side-by-side relation. The description of a single device and the explanation of the wiring diagram, Fig. 9, will make this clearly evident. As shown in Fig. 9, electrical feed wires *a* and *b* are extended through a series of plurality of devices, and electrical connections are made with the devices through pairs of wires *a'*—*b'* and *a''*—*b''*. The feed wires *a* and *b* are supplied with electric current from a suitable source, such as a transformer 63, through a circuit 64 having a switch 65 which may be manipulated by the operator of the games so as to turn them on or off simultaneously and to reset the games for further play after a game has been completed.

For purpose of explanation, the game device 20 may be said to have a buss wire *A* and a wire *B* respectively connected to the feed wires *a* and *b*, and when any electrical device or element of the game device, or devices, is connected to both of these wires *A* and *B*, it will be electrically energized. The lamps 48a, of which there are fifteen shown arranged in the form of an outer circle, all have one terminal thereof connected to the buss wire *B*. The opposite terminals of the lamps 48a are connected through fifteen wires 66 with fifteen contacts 67 of a switch 68 which is normally open and which has a solenoid 69 for closing it. The wires 66 are also connected to fifteen wires 71 which extend to a like number of contacts 72 forming part of a rotary switch 73 which is mounted as shown in Figs. 4 and 6 at the lower end of the shaft 29 so as to rotate with the shaft. The contacts 72 are carried by a ring 74 of insu-

lating material supported by a bracket 75, and a radial contact 76 is secured to the lower end of the shaft 29 so that as the shaft 29 rotates, the contact 76, which is in the form of a brush, will consecutively engage the contacts 72. By means of a mounting 77, a spring contact 78 is held so that it will engage the inner end of the contact or brush 76, and this spring contact 78 connects through a wire 79 with the wire *A*. As the motor 33 operates the shaft 29 and the turntable 27, the brush 76 will consecutively engage the contacts 72 so that the lamps 48a will be consecutively energized to give the effect of a light traveling around the circle of indicators 48 on the board 46. The wires 71 may be connected between the switch contacts 72 and the lamps 48a so that the light produced in the circle of lamps 48a will move forwardly or in reverse direction or skip back and forth in accordance with the novel effects desired.

The switch 68 contains fifteen movable contacts 81 adapted to be brought into engagement with the contacts 67. These movable contacts 81 are all connected together or bridged by means of a buss bar 82 which is also connected to movable contacts 83 and 84. A stationary contact 85 is placed so as to be engaged by the contact 84, and this contact 85 is connected through a wire 86 to the wire *A* so that when the switch 68 is closed, all of the contacts 81 will be energized and through the contacts 67 and the wires 66 will energize all of the lamps 48a at the same time. The contact 83 will at the same time engage a contact 87 and through a wire 88 close a hold-in circuit for the coil 89 of the solenoid 69 forming a part of the switch 68. The movable part 91 of the switch 68 also carries bridged or connected contacts 92 adapted to be carried into engagement with stationary contacts 93 to close a circuit 94 connecting the *B* wire with one side of the coil 95 of a center switch *C*.

Each of the fifteen openings 38 of the turntable 27 has a switch 96 associated therewith, as shown in Figs. 1, 4, and 5. Each of the switches 96 has a movable contact 97 which is connected to the buss wire 98 extending down through the hollow shaft 29 to a ring 99 connected by a brush 101 with the circuit wire *A*. Each switch 96 also has a contact 102, these contacts 102 being connected through wires 103 which extend down through the hollow shaft 29 to contacts 104 mounted in circular arrangement on annular insulators 105. As the shaft 29 rotates, the contacts 104 are consecutively brought into engagement with a brush 106 which is connected through a wire 107 with the wire 88 which is in turn connected to the coil 89 of the switch 68. The brush 106 is so placed that it will engage the contact 104 which is connected through a wire 103 with the switch 96 associated with the opening 38 disposed adjacent a mark 108 at the back of the playing board 22, as shown in Fig. 1. Accordingly, if the player causes a ball to drop through an opening 38 at the time the opening is passing the mark 108, the switch 96 will be closed, thereby energizing the coil 89 of the switch 68, with the result that all of the lamps 48a will be lighted. For example, with the switch indicated by 96a in Fig. 9 closed by a ball at the time such switch is opposite the mark 108, the circuit including the wire 103a and the wire 107 will at the same time be closed by the brush 106, and the switch 68 will be electrically closed and will be held closed by the hold-in circuit formed by the wire 88 until the switch 65 controlling the entire electrical sys-

tem is opened. Accordingly, all of the circle of lights 48a will remain illuminated until the completion of the game or until the game is reset by the operator.

5 Each of the star-point openings 41 to 45 inclusive has a switch 111, similar to the switches 96, associated therewith, and each switch 111 has a movable contact 112 connected with the buss wire 91 which is connected through the 10 ring 99 and the brush 101 with the wire A. The switches 111 also have cooperating contacts 113 connected through wires 114 with collector rings 115. Brushes 115a connect the rings 115 respectively through wires 116 with solenoids 117 of 15 switches S, respectively indicated as S1, S2, S3, S4, and S5, in accordance with the lamps 51a to 55a with which they are connected through wires 118 and 119. Each switch S has a pair of light control contacts 121 and 122 at the left-hand side thereof respectively connected to the 20 lights 51 to 55 and to the wire A, and a pair of contacts 123 and 124 which are in series in a loop circuit 125. The left-hand end of the loop circuit 125 is connected to the contact 122 25 of the switch S1 which is in turn connected to the wire A. The right-hand end 126 of the loop circuit 125 is connected through the coil 127 of a master switch M with the wire B. Accordingly, when the contacts 123 and 124 are all 30 closed or connected, the switch M will be closed, completing the playing of the game.

The switches S have movable contacts 128 for closing or connecting the contacts 121 and 122, and movable contacts 129 for connecting the contacts 123 and 124. Hold-in circuits for the switches S are produced by wires 131 which connect the contacts 121 with the wires 116 leading to the coils 117 of the respective switches S. The switch M has a pair of contacts 130 and 130a adapted to close a hold-in circuit connecting the wire A with the wire 126. For continuing the energization of the coil 127, the switch M has a pair of contacts 132 and 133 for closing a circuit 134 from the wire a' to the wire b' through a coil 135 of a cut-out relay 136, disposed between the wire a' and the wire A, this relay or switch 136 being normally closed as shown in Fig. 9 and when open being adapted to disconnect the wire A from the current supply system having a wire a to which the wire a' is connected as 50 previously described.

In the playing of the game, one way to produce a winning score is to close the five switches 111 so as to light all of the lamps 51a to 55a forming or defining the points of the star. This will 55 close all of the relay switches S1, S2, S3, S4, and S5 so that the closing of the loop circuit 125 will result in closing the switch M and consequently opening the cut-out relay 136, but the opening of the relay 136 will not turn out the lamps 51 to 55a for the reason that the wire A will continue to be energized through the wire 134, the contact 132, movable contact 131, and the contact 130a after the opening of the cut-out relay 136. The play on all game devices which may be connected with the game device shown will be stopped. The wire c' is connected from the contact 133 of the switch M to a feed wire c extending parallel to the wires a and b. 60 The wire c is energized, when the switch M closes, from the wire a through the wire a', wire 134, contacts 133 and 132, and the wire c'. The wires c and c' are in parallel with the wires a' and A, and any electrical device connected across the 65 wires c and b will be energized. In the lower 70 wires c and b will be energized. In the lower

left-hand corner of Fig. 9, wires a'', b'', and c'' are shown extending from the wires a, b, and c, these wires a'', b'', and c'' corresponding in function to the wires a', b', and c' in the operation and control of an associated game device constructed and played in the same manner as the game device 20 disclosed in the drawings. Through energization of the wire c', the cut-out relay 136 will be opened. This is also true of the cut-out relay of any associated device connected to the wire c through a control wire such as the wire c''. The lights of the winning game will remain energized, but the lights of all of the remaining, or non-winning, games will be cut off due to the opening of the cut-out relays 15 136 thereof before the closing of the respective relays M of the non-winning devices.

The winning of the game by placing a ball in each of the five holes 41 to 45 of the turntable 27 has been disclosed. Another way of producing a winning score is to first light up the outer circle of lights 48a, as previously described, and then to place the ball in the center opening 40. This will close the switch 139 which is connected to the buss wire 98 and is also connected 20 through a ring 141, a brush 142, and a wire 143 with one side of the coil 95 forming a part of the center switch C. Unless the switch 68 has been first closed, the closing of the switch 139 cannot energize the coil 95 for the reason that 25 the circuit through the coil 95 from the wire A to the wire B will be open at the contacts 93 which are closed only by the actuation of the switch 68. But should the switch 68 have been first closed by the proper placing of a ball in 30 an opening 38 as it passes the mark 108, the center switch C may be closed by placing a ball in the center hole 40 of the turntable 27. This will result in not only lighting the lamps 48a and 50a, but also the lamps 51a to 55a, for the 35 reason that the switch 95 has contacts 145 connected to the lamps 51a to 55a through the wires 119, a contact 146 connecting with the lamp 50a through a wire 147, a contact 148 connected to the wire A, and contact means 149 40 45 for connecting all of the contacts 145 and 146 with the hot contact 148. A hold-in circuit for the coil 95 is formed by a wire 151 connecting one of the contacts 145 with the coil 95.

Since the hold-in circuit wire 131 of each 50 switch S is connected through a wire 118 with a wire 119, the closing of the switch C will cause the closing of all of the switches S, which will in turn close the loop circuit 125 extending to the coil 127 of the master switch M to finally 55 produce the energization of the coil 135 and opening the cut-out relay 136. Simultaneously with the opening of the cut-out relay 136, the wire c will be energized so that the cut-out relays connected thereto and forming the control means 60 of associated games will be instantaneously opened to cut off the electrical energy of all of the associated games, turning out the lights thereof, and thereby preventing further play on such associated games, all as the direct result 65 of producing a winning score on the "winning" game.

The winning of a game on one of the associated devices, energizing the wire c, results in the ringing of a bell 155 in a circuit 156 which is bridged 70 across the wires b and c. The circuit 156 has a switch 157 therein whereby the ringing of the bell may be stopped without destroying the showing of the winning score on the winning game device. To reset the game device, and the asso- 75

ciated game devices, for further play, the switch 65 may be opened so that the wires A and B of the game or games will be de-energized, all of the relays 68, C, S, and M opened, and the cut-out relays 136 reclosed. When the switch 65 is again closed, the play may be continued, for the closing of the switch 65 results in re-energizing the wires A and B.

I claim as my invention:

- 10 1. An electric game device of the character described, including: a driven turntable having a plurality of ball-receiving stations; a marker adjacent the turntable; a normally open switch at one of said stations and adapted to be closed temporarily by a ball reaching said station; a second normally open switch; a first circuit including said two switches in series; means to close said second switch temporarily when said station is at a predetermined point with respect 15 to said marker whereby said circuit will be closed whenever a ball reaches said station when the station is at said predetermined point; a relay controlled by said circuit and adapted to be closed when the circuit is energized; a third normally open switch associated with a second ball-receiving station on the turntable adapted to be temporarily closed by a ball reaching said second station; and a signal circuit controlled by said relay and said third switch whereby said signal 20 circuit will be energized whenever a ball reaches said second station while said first circuit is closed.
- 25 2. An electric game device of the character described, including: a turntable having means for rotating the same; a circular series of switches thereon, each adapted to be closed by a ball; a circular series of lamps in the field of vision from said turntable to serve as an indicating means; means for intermittently flashing said lamps when the turntable rotates; a marker adjacent the turntable; and means operatively associated with 30 said series of switches to light all of said lamps

whenever a ball closes one of said switches at a predetermined position relative to said marker.

3. An electric game device of the character described, including: a turntable having means for rotating the same; a circular series of primary 5 switches thereon, each adapted to be closed by a ball; a circular series of lamps in the field of vision from said turntable; means for intermittently flashing said lamps when the turntable rotates; a marker adjacent the turntable; means for lighting all of said lamps when a ball closes one of said switches while it is in a predetermined relation to said marker; a secondary switch on said turntable adapted to be closed by a ball; and means responsive to the closing of said secondary 10 switch after all of said lamps are lighted to indicate the winning of the game.

4. An electric game device of the character described, including: a turntable having means for rotating the same; a circular series of first 15 switches on said turntable, each adapted to be closed by a ball; a circular series of first indicators in said field of vision corresponding to said first switches; a marker adjacent the turntable; means for actuating all of said indicators 20 when one of said switches is closed while it is in a predetermined relation with said marker; a second switch on said turntable adapted to be closed by a ball; a second indicator in said field of vision corresponding to said second switch; 25 means for operating said second indicator in response to closing of said second switch after the actuation of all said first indicators; a plurality of third switches on said turntable, each adapted to be closed by a ball; a plurality of third indicators corresponding with and controlled by said third switches; and means responsive either to the 30 operation of said second indicator or to the operation of all said third indicators to indicate the winning of the game.

JAMES H. CANNON.
